(57) **CLAIM**

I claim the ornamental design for a light fixture, as shown
and described.

DESCRIPTION

FIG. 1 is a front perspective view of a light fixture showing
my new design.

FIG. 2 is a side elevational view taken from the left side of
FIG. 1.

FIG. 3 is a side elevational view taken from the right side of
FIG. 1.

FIG. 4 is a top plan view thereof.

FIG. 5 is a bottom plan view thereof; and,

FIG. 6 is a bottom plan view of an alternate embodiment.
